UNITED STATES PATENT OFFICE.

BENJAMIN F. WOODHOUSE, OF MORRIS RUN, PENNSYLVANIA.

TRACE-FASTENER.

No. 922,992.

Specification of Letters Patent. Patented May 25, 1909.

Application filed February 24, 1909. Serial No. 479,782.

To all whom it may concern:

Be it known that I, BENJAMIN F. WOODHOUSE, a citizen of the United States, and a resident of Morris Run, county of Tioga, 5 and State of Pennsylvania, have invented a certain new and useful Trace-Fastener, of which the following is a specification.

The principal object is to provide a comparatively simple and inexpensive trace fastener which may be applied with ease and facility and which is positive in action and not liable to accidental disengagement.

To the end stated, the invention consists in the improvements hereinafter described 15 and claimed.

The nature, characteristic features and scope of the invention will be more clearly understood from the following description taken in connection with the accompanying 20 drawing, forming a part hereof, and wherein—

Figure 1, is a perspective view of a trace fastener embodying features of my invention. Fig. 2, is a similar view with the 25 parts disengaged. Fig. 3, is a view principally in section showing the members interlocked; and Fig. 4, is a sectional view of the trace member.

Referring to the drawings, A and B, denote 30 the respective interlocking locking members of my improved trace fastener. The member A, may be secured rigidly to the trace in the general plane thereof as in Figs. 2 and 4, or it may be pivotally attached as in Figs. 1 35 and 3. Said member A, is provided at one side with a longitudinally ranging channel or groove a , which merges into a transversely ranging slot a' , one wall a^2 , of the slot being substantially in obtuse angle in 40 cross section, Figs. 3 and 4, and the other

wall being inclined and having an overhang, ledge or projection a^3 .

The swingle tree member B, is L-shape, and one arm b , is tapered or cone-shape and penetrates and frictionally engages a correspondingly formed bore in the ferrule C of the swingle tree. The locking element b' , extends in the general plane of the trace and is provided with a tongue or projection b^2 , which is a solid counterpart of the slot 50 or socket a' , except that it has an undercut portion b^3 , to enable it to pass and then engage the abutment or wall a^2 . There is also a rabbeted part b^4 , to engage the ledge or projection a^3 .

From the foregoing it is manifest that to bring the parts into engagement it is necessary to tilt them relatively to one another, and that a pull on the trace acts simply to accelerate the locking of the parts.

Having described the nature and objects of the invention, what I claim as new and desire to secure by Letters Patent is:—

A trace fastener comprising interlocking members whereof one is channeled and slotted, the slot being provided with an overhang, ledge, or projection and with an angular abutment and whereof the other member is provided with a rabbeted portion to engage said overhang and with an undercut tongue that penetrates the slot and engages said abutment.

In testimony whereof I have hereunto signed my name in the presence of two subscribing witnesses.

BENJAMIN F. WOODHOUSE.
